UNITED STATES PATENT OFFICE

2,419,490

CONVERTIBLE VACUUM CLEANER

Malcolm W. Fraser, Maumee, Ohio, assignor
to Air-Way Electric Appliance Corporation,
Toledo, Ohio, a corporation of Delaware

Application July 17, 1944, Serial No. 545,232

5 Claims. (Cl. 15—14)

1

This invention relates to vacuum cleaners of the type in which dust laden air entering the machine passes directly into a dust collecting filter and thence is pulled through the filter into the suction producing unit from which it is discharged from the machine. In particular, the invention relates to a cleaner of this type having a single outlet through which the discharge may be concentrated and delivered through a suitable hose attachment to various types of blowing devices. An object of the invention is to provide a vacuum cleaner of this type, wherein the full capacity of the suction unit may be automatically delivered to the blower outlet merely by application to the cleaner of the blower attachment.

In all vacuum cleaners, the filter offers a definite obstruction to the passage of air and reduces the flow of air that the suction unit would be capable of producing if unimpeded by the filter. This flow is further greatly reduced by the accumulation of dust and debris in the filter. When the filter becomes filled, the air flow may be reduced to only a fraction of its original quantity. Any material loss in air flow seriously impairs the efficiency of the blower attachment, particularly spraying devices which require a certain head of air pressure in order to operate satisfactorily.

The present invention makes it possible to relieve the suction unit of the filter load by providing means for automatically enabling air to flow directly to the inlet of the suction unit without passing through the filter when the blower attachment is connected to the machine.

Another object is to provide a vacuum cleaner with automatic means responsive to the mounting of the blower attachment thereon for utilizing the full force of the air stream created by the fan unit by taking in air from the outside without the necessity of having it pass through the filter.

Other objects and advantages will hereinafter appear and for purposes of illustration but not of limitation, embodiments of the invention are shown in the accompanying drawings in which

Figure 1 is a side elevation of a vacuum cleaner disposed on its side in the position where the blower attachment may be mounted;

Figure 2 is an enlarged fragmentary view of a vacuum cleaner of the upright type, parts being broken away and shown in section to illustrate the means by which the valve is unseated for enabling the fan unit to draw in air directly from

2

the outside instead of drawing air through the filter unit;

Figure 3 is an enlarged fragmentary sectional view showing the valve arrangement illustrated in Figure 2 with the valve in closed position;

Figure 4 is an enlarged sectional view substantially on the line 4—4 of Figure 2;

Figure 5 is a fragmentary sectional view showing an alternate form in which the valve is electromagnetically actuated to its open position; and

Figure 6 is an enlarged detail sectional view of the electromagnetically actuated valve with the valve in open position.

The illustrated embodiment of the invention comprises a vacuum cleaner of the upright type including a base 10 having supporting legs 11, a housing having a shell 12 rising from the base 10, and a filter casing 13 mounted on the shell 12. A suction unit 14 is supported within the shell 12 and a filter 15 is suitably suspended within the filter casing 13. The top of the filter casing 13 is closed by a suitable cover 15, which is provided with an inlet neck 16 to which may be attached the usual hose leading to a suitable cleaning tool (not shown). The filter 15 in this instance is in the form of porous paper, cloth or other air pervious material and is suitably supported between the top of the casing 13 and the cover 15.

The suction unit 14 comprises a motor and fan assembly which includes a housing 17 on the upper portion 18 of which is mounted an electric motor 19. The lower portion of the housing 18 is enlarged at 20 to form the fan casing within which is mounted a conventional type of multiple, centrifugal, impeller suction fan unit of a type adapted to produce a high suction head.

The shell 12 in this instance is formed with a bottom wall 21 which has a blower outlet or outlet tube 22 through which the discharge from the suction unit 14 may be concentrated. The housing 18 of the suction unit 14 has a diaphragm 23 supported by a flanged ring 24 secured to the inner wall of the shell. The diaphragm 23 separates the space within the shell 12 into an inlet chamber 25 which is in direct communication with the filter casing 13, and a discharge chamber 26, which communicates with the chamber 25 only through the suction unit. The discharge chamber 26 is closed except for the blower outlet 22.

In cleaning operations, dust laden air is drawn into the machine through the inlet neck 16, and passes directly into the filter bag 15 through which

the air is filtered and drawn into the inlet chamber 25. From the chamber 25, the air passes through an inlet 27 into the suction unit 14, thence through the fan and out of a discharge outlet 28 of the suction unit, thence into the chamber 26, and thence through the outlet 22 to the outside.

In blowing operations, the hose is detached from the inlet neck 16 and a hose 29 with the blowing attachment thereon is applied to the outlet 22. It will be recognized that the volume of air drawn through the filter bag 15 depends upon the extent to which the pores of the filter bag are clogged. The more the filter bag 15 is clogged, the smaller will be the volume of air discharged at the outlet 22.

In accordance with this invention, when it is desired to make use of the blowing attachment, a valve is automatically opened enabling the suction unit 14 to draw in air or at least a portion of the air directly from the outside without the necessity of it passing through the filter bag. As shown, a valve seat 30 in the form of an annular collar providing an inlet opening 31 projects outwardly from the wall of the shell 12 in communication with the inlet chamber 26. The valve comprises a stem 32 which slides in a bracket 33 secured to the inner wall of the shell 12 and fastened to the outer end of the stem 32 is a head 34 having a rubber washer 35 for engagement with the annular seat 30. A coil spring 36 is interposed between the bracket 33 and a washer 37 on the inner end portion of the stem 32. A nut 38 engages the threaded inner end of the stem to hold the washer 37 in adjusted position.

The spring 36 normally holds the valve head 34 in closed position but in order to unseat the valve automatically upon the insertion of the hose 29 within the discharge tube 22, a rod 39 is mounted for sliding movements in brackets 40 and 40A and the flanged ring 34 is provided with a cam 41 on its upper end engageable with a pin 42 which extends through the valve stem 32. As shown, the cam member 41 is formed with an elongate aperture through which the stem 32 extends. It will be obvious upon inspection of Figures 2, 3 and 4 of the drawings, that when the hose member 29 of the blowing attachment is inserted into the outlet opening 22, it abuts against an inturned end 43 of the rod 39 and moves the same upwardly so that the cam 41 operating against the pin 42 moves the valve head outwardly or to the position indicated on Figure 4. In such a position, the fan unit can draw air directly through the opening 31 and without the necessity of requiring the air to pass through the filter unit 15.

As soon as the hose 29 is removed from the opening 22, the rod 39 is moved downwardly in response to a coil spring 44, one end of which bears against a disc 45 fixed to the rod and the other end of which bears against the bracket 40A. Upon downward movement of the rod 39 to its normal position with the end thereof resting against the discharge tube 22, the spring 36 moves the valve head 34 abruptly to its seat.

The alternate form of the invention illustrated in Figures 6 and 7 contemplates the actuation of the valve to its open position by electromagnetic means. In this instance the valve stem 32' has a valve head 34' with a similar rubber gasket and supported on the inner wall of the shell 12 is a bracket 46 supporting a solenoid 47 through which the valve stem 32' reciprocates. A coil

spring 48 is interposed between the solenoid and a washer 49 at the inner end of the stem 32' for normally holding the valve in its seated or closed position. It will be understood that upon energizing the solenoid 47, the valve stem 32' is moved to the left of the figures substantially to the position shown in Figure 6 and holds the valve in that position until deenergized. From the solenoid 47 extends a lead 50 which is suitably connected to a switch element 51 so arranged that when the blower hose 29 is inserted into the outlet tube 22 to the proper distance, the switch is closed, thereby to energize the solenoid 47. When the blower hose 29 is removed, the spring action of the switch unit 51 breaks the electrical connection and the solenoid 47 is deenergized. Thereupon the coil spring 48 automatically seats the valve head 34'.

It will be manifest that in each of the above forms, the valve is automatically moved to its open position when the blower hose is inserted into the outlet tube or opening and in this manner more satisfactory and efficient blowing operation can be carried on. However, as soon as the blower attachment is removed from the vacuum cleaner, the valve is automatically closed, thereby obviating the necessity of the operator manually closing the valve. In this way the device is fool proof and in no instance will the valve be in its open position when the vacuum cleaner is employed for suction cleaning operation.

It is to be understood that numerous changes in details of construction, arrangement and operation may be effected without departing from the spirit of the invention especially as defined in the appended claims.

What I claim is:

1. In a vacuum cleaner of the type including a dust collecting filter, a suction unit arranged to pull air through said filter, and a housing providing a closed chamber with which the inlet side of said suction unit and the discharge side of said filter communicate, a valve in said housing adapted when in open position to afford communication between said chamber and the outside for by-passing inlet air to said suction unit, means providing an outlet chamber on the discharge side of the suction unit, means leading to the interior of said outlet chamber providing for the attachment of a blower hose, and means responsive to the attachment of a blower hose to said last means for moving said valve to its open position.

2. In a vacuum cleaner including a dust collecting filter, a suction unit, and a housing forming a closed chamber with which the inlet side of said suction unit and the discharge side of said filter communicate, and an outlet chamber with which the outlet of said suction unit communicates, said outlet chamber having an outlet for receiving the hose of a blower attachment, a valve in the wall of said housing communicating with said first mentioned chamber, and means engageable with said blower hose upon attachment of same to said outlet for causing movement of said valve to open position.

3. A vacuum cleaner as claimed in claim 2, wherein said valve unseating means comprises mechanically operated means including a spring tensioned longitudinally movable rod for unseating said valve, and spring means for moving said valve to its seat upon removal of the blower hose.

4. A vacuum cleaner as claimed in claim 2, wherein said valve unseating means comprises a

spring tensioned cam means for moving said valve away from its seat, and spring means for returning said valve to its seat.

5. A vacuum cleaner of the type including a dust collecting filter, a suction unit arranged to pull air through said filter, and a housing providing a closed chamber with which the inlet side of said suction unit and the discharge side of said filter communicate, said filter being of porous material, impervious to dust particles but pervious to air in a degree that decreases with the accumulation of dust in said filter, a valve in said housing adapted to provide communication between said chamber and the outside for by-passing inlet air to said suction unit around said filter, means for automatically opening said valve upon application of a blowing attachment to the vacuum cleaner, and spring means for closing said

valve upon removal of such blowing attachment.
